FIG. 1 is a right side, top and rear perspective view of a collapsible rear projection viewer accessory for a slide projector or similar article, showing my new design in erected position;

FIG. 2 is a rear, top and right side perspective view in collapsed position;

FIG. 3 is a top plan view in collapsed position;

FIG. 4 is a bottom plan view in collapsed position;

FIG. 5 is a right side elevational view in collapsed position, the opposite side being substantially a mirror image thereof;

FIG. 6 is a right side elevational view in erected position, the opposite side being substantially a mirror image thereof;

FIG. 7 is a top plan view in erected position;

FIG. 8 is a front elevational view in erected position; and

FIG. 9 is a rear elevational view in erected position.

The broken line fragmentary showing of a representative slide projector in FIG. 1 is for illustrative purposes only. The lower mirror is flat surface shaded on the back side in FIGS. 1 and 9 to indicate an opaque surface and the upper viewing screen is diagonally lined on both sides thereof to indicate a translucent material.

I claim:

The ornamental design for a collapsible rear projection viewer accessory for a slide projector or similar article, as shown and described.
